AMPLIFIER CABINET OR SIMILAR ARTICLE

Victor Pomper, 45 Linnaean St., Cambridge, Mass.

Filed July 16, 1959, Ser. No. 56,810

Term of patent 14 years

(Cl. D26—14)

The single figure of the drawing is a front isometric view of an amplifier cabinet or similar article, showing my new design, the rear view being identical with the front view.

The drawing is shaded to indicate contrast in appearance.

I claim:

The ornamental design for an amplifier cabinet or similar article, substantially as shown and described.
